UNITED STATES PATENT OFFICE.

BENJAMIN Q. BUDDING, OF MILFORD, MASSACHUSETTS.

IMPROVED MACHINE FOR POLISHING HEELS OF BOOTS AND SHOES.

Specification forming part of Letters Patent No. 42,555, dated May 3, 1864.

To all whom it may concern:

Be it known that I, BENJAMIN Q. BUDDING, of Milford, in the county of Worcester and State of Massachusetts, have invented an Improved Machine for Polishing the Heels of Boots and Shoes; and I do hereby declare that the following, taken in connection with the drawings which accompany and form part of this specification, is a description of my invention sufficient to enable those skilled in the art to practice it.

The nature of my invention consists in so constructing and arranging the operative parts of a machine for polishing the heels of boots and shoes that I am enabled by hand manipulation to turn the heel about in all directions while it is held against a vibrating polisher, whereby a much better finish or polished surface is imparted to the curved surface of the heel than can be given by hand or by a machine so made as to vibrate a polishing tool or tools over the surface of the heel against which they are held, while the shoe is jacked or fastened upon a stationary rest.

In the ordinary use of a polishing or rubbing stick or tool by hand the tool is rubbed to and fro over the surface of the heel to be polished, and the position of the tool with respect to such surface continually changed by the operator as one part or another may require more or less rubbing.

The pressure required to so harden or solidify and polish the surface is very great, requiring much outlay of strength, the operation being a tedious and laborious one; yet the skill of intelligent direction and manipulation of the tool by the operator has been found to answer the requirements of this work much better than when the operation is performed entirely by an automatic mechanism, because there are always parts of the surface to be polished requiring a greater rubbing than others, while such parts vary in position and are dependent very much upon the varying qualities of the stock used in the construction of the heel.

My present machine differs from the heel-polishing machine on which patent numbered 39,546 was granted to me, as in that machine there existed no means for turning the heel or shoe by hand, the shoe being held rigidly upon a fixed support during the automatic operation of the polishers. I have found, however, from

experiments with these machines and with the machine herein described, that for the purpose of polishing heels to the best advantage it is necessary not only to hold the work up against the vibrating polisher and with a spring or yielding pressure between the polisher and the heel, but to combine therewith a means for easy and rapid turning of the work or heel around to the action of the polishing-tool, so that the extent of action of the tool over different parts of the surface to be polished may be varied as circumstances may require, as above described, and my machine, embodying these features, is shown in the top view or plan in Figure 1 of the accompanying drawings, in side elevation in Fig. 2, and in front elevation in Fig. 3.

a denotes the table upon which the machine is placed; *b b* two standards rising therefrom and uniting at top, so as to make or support a journal or bearing for a horizontal rocker-shaft, *c*. On the rear end of this shaft is placed a collar or wrist, *d*, from the upper surface of which a leaf-spring, *e*, extends horizontally over the shaft *c*, the spring carrying at its opposite end the polisher or polishing iron or tool *f*, whose position is just in front of and above and in a vertical plane with the shaft *c*, and immediately over the heel to be polished, as seen in Fig. 2. From the crank-pin of a wheel, *g*, fixed on a driving-shaft, *h*, a connecting rod or link, *i*, extends, the upper end of the rod being jointed to a crank or arm, *k*, projecting from the shaft *c*. Rotation of the shaft *h* imparts a rocking motion to the shaft *c*, and thereby communicates to the spring *e* and its polisher *f* a rotary and vibrating movement, as will be readily understood. Parallel to the shaft *c*, and at a little distance from the same, is placed in bearings *m* another shaft, *n*, on the front end of which is fixed an arm, *o*, which projects toward the shaft *c*, as seen in Fig. 3. A rotating pin, *p*, projects from and turns freely in the end of this arm, and carries in its outer end a screw-pin, *q*, from which hangs, and so as to freely swing or turn therein, a jack or plate, *r*, to which the shoe is to be fastened. The plate hangs directly under or so as to bring the heel of the shoe directly under the polisher *f*, as seen in Figs. 2 and 3. While the rotation of pin *p* permits the plate *r* to be freely turned thereupon, the screw-pin *q* allows of its re-

tation in a plane perpendicular thereto, the two devices forming a universal joint and allowing of movement of the entire surface of the heel into contact with the surface of the vibrating polisher, and at all angles of inclination with respect thereto necessary to rub the leather in contrary directions, so as to rapidly and easily solidify and burnish the surface thereof. An arm, *s*, extends down from the rear end of the shaft *n*, and to this arm is fastened a cord, *t*, which, passing through the table on one side of the arm, has a weight tied upon it, the weight actuating the arm *s*, shaft *n*, and arm *o*, and holding the heel up against or into contact with the surface of the polishing-tool. Pressure of the foot upon a treadle lever, to which the cord *t* might be attached, or a spring or a mechanism for locking the arm *s* in position, may be employed instead of the means described for holding the heel against the polisher; but I generally prefer the use of the weight for this purpose.

The operation of the machine may be understood from the above description, or, succinctly, is as follows: Motion being given to the driving shaft *h*, the tool *f* is vibrated rapidly over the surface of the heel, which is held up against it by the weight, while the operator, through the means of the freely suspended and rotary plate *r*, turns the heel in all desirable directions, as specified. The spring *e* allows the polisher to yield to any inequality of surface upon the heel, and the surface of the polisher has such a convexity as will permit of its extending into and rubbing into shape the concave surface of the heel.

I construct the polisher hollow, (as seen in Fig. 4, which denotes a cross-section of it,) and provide it with a slide, *l*. In this hollow I place a heating-iron, *u*, so that when desirable the surface of the polisher may be heated thereby, the iron being taken out and replaced, as occasion may require, by removing the slide *l*.

The plate or jack *r* is provided with a shoulder, *v*, against which the inner side of the

heel rests, and with a strap, *w*, which passes around the back of the shoe, as seen in Figs. 2 and 3. The opposite ends of the strap are fastened to pins *x*, projecting from arms *y*, which extend from cogged sectors or ratchet-wheels *z*, rotating on pins *a*², as will be understood from Fig. 5, which represents a rear view of the plate. One of the arms, *y*, has a handle, *b*², and a pawl, *c*², is hung upon the back of the plate. To fasten the shoe firmly to the plate, the inner side of the heel is placed upon the shoulder *v*, (which may be provided with teeth or pins to penetrate the heel,) with the sole of the shoe resting upon the outer surface of the plate. The strap then being carried around or slipped over the back of the shoe, (which is, of course, upon a last,) the handle *b*² is depressed, which depresses its pin *x*, and one cogged sector or ratchet, meshing into, turns the other, which depresses simultaneously the other arm, *y*, and pin, *x*, and draws the strap tightly upon the shoe, or the heel upon the shoulder *v*, when the pawl *c*² is slipped into the ratchet and holds it fast.

Instead of the two ratchets or sectors, only one may be used, the opposite pin *x* being made stationary; but as that would have a tendency to twist the heel in drawing the strap down to fasten the shoe upon the plate, I generally prefer to use them both, as set forth.

I claim—

1. In combination with a polishing tool which has a vibratory movement imparted to it, a mechanism which allows the shoe to be freely turned by hand in every direction necessary to bring all parts of the heel to be operated upon into contact with the polishing-tool.
2. The construction of the plate *r*, with the shoulder *v*, ratchet or ratchets *z*, pawl *c*², and strap *w*, or their equivalents, substantially as set forth.

B. Q. BUDDING.
